CLAIM

We claim the ornamental design for a headset respiration faceplate, as shown and described.

DESCRIPTION

FIG. 1 is a front perspective view of a headset respiration faceplate, according to an exemplary embodiment of the present disclosure;

FIG. 2 is another front perspective view thereof;

FIG. 3 is a rear perspective view thereof;

FIG. 4 is a front side elevation view thereof;

FIG. 5 is a rear side elevation view thereof;

FIG. 6 is a right side elevation view thereof;

FIG. 7 is a left side elevation view thereof;

FIG. 8 is a top side elevation view thereof; and,

FIG. 9 is a bottom side elevation view thereof.

The broken lines in the drawings illustrate environmental structure or boundaries that form no part of the claimed design.
